UNITED STATES PATENT OFFICE

2,178,040

PRESSURE FEED CARBURETOR

Joseph Hewitson, Kalispell, Mont.

Application April 22, 1937, Serial No. 138,443

5 Claims. (Cl. 123—119)

This invention relates to a pressure feed carburetor, and an object is to improve the construction of carburetor disclosed in Letters Patent issued to me on February 16, 1937, No. 2,070-598, for improvements in Pressure feed carburetors.

Additional objects are to provide novel means wherein the feed of the fuel under pressure is thermostatically controlled and particularly by 10 means located in a chamber or the like through which exhaust gases, or air heated from the engine, travels, or other heating means provided.

It is also aimed to provide a novel fan mechanism for increasing turbulence and supercharging in a mixing chamber, and which fan is operable by a turbine driven by the said exhaust or other heating medium.

A further object is to provide novel means for more efficiently preheating the fuel and a novel 20 auxiliary air valve means which is controlled by the load change and the resultant throttle movement that changes the intensity of the vacuum in the engine manifold.

The more specific objects and advantages will 25 become apparent from a consideration of the description following taken in connection with accompanying drawings illustrating an operative embodiment.

In said drawings:

30 Figure 1 is a plan view of the improved pressure feed carburetor;

Figure 2 is a vertical sectional view taken substantially on the plane of line 2—2 of Figure 1;

Figure 3 is a horizontal sectional view taken 35 substantially on the plane of line 3—3 of Figure 2;

Figure 4 is a vertical sectional view taken on the plane of line 4—4 of Figure 3;

Figure 5 is a horizontal section taken on the plane of line 5—5 of Figure 2;

40 Figure 6 is a detail section taken on the plane of line 6—6 of Figure 1, and

Figure 7 is a diagrammatic view of the details of the structure of Figure 5.

Referring specifically to the drawings wherein 45 like reference characters designate like or similar parts, the carburetor comprises inner and outer castings or cylinders 10 and 11, having spacing rings 12 and 13, therebetween, at the top and bottom, and a plate 14 also extends across the top of the carburetor and is secured to said cylinders and ring 12 while at the bottom, a pipe or conduit member 15 is rigidly or detachably secured to the said cylinders 10 and 11 and ring 13, as through the medium of a flange 16. The 50 usual throttle-valve 17 is pivotally mounted on

a spindle 18 journaled diametrically of the conduit section 15 and such section is attached immediately or immediately to the intake manifold of the internal combustion engine in connection with which the carburetor is used. Centrally of 5 the plate 14, an air inlet port 19 is provided, which is adapted to be closed or opened to variable degrees as will later be explained.

Attached to the outer cylinder 11 is a block 21. This block, if desired, may be made integral with 10 such cylinder. The block has a fuel inlet passage 22 connected with a pipe 23, in communication with any suitable source of fuel supply, for instance gasoline. Passage 22 has a lateral extension 24 provided with a valve seat 25 with 15 which a main or fuel control needle valve 26 slidably co-acts. Said passage 22 beyond the seat communicates with a fuel supply pipe 26', preferably U-shape or otherwise extended in the space between cylinders 10 and 11 and hereafter 20 referred to as a heating chamber. Pipe 26' terminates in an enlarged portion or outlet nozzle 28, preferably disposed diametrically across a super-heating or mixing chamber 29, such nozzle 28 25 preferably having a multiplicity of outlet orifices 30 35 diametrically arranged.

In the block 21 aforesaid, branches 32 and 33 are provided in communication with the passage 22. A needle valve 34, for idling adjustment, is screw threaded to the block at 35 and co-acts 30 with a seat 36 at the junction of the passages 32 and 33. From the passage 33, a tube 37 leads, extending downwardly through the heating chamber 27 and communicating with a passage 38 extending through ring 13 and conduit section 15 and opening into the interior of the latter, adjacent the throttle-valve 17.

Vacuum operated means is adapted to bleed air into the main fuel pipe or passage 27 and also into the idling fuel pipe or passage 37. To this end, as best shown in Figure 5, a passage 39 is arranged in communication with the passage 33 and a passage or port 40 is arranged in communication with passageway 24. A plate or ring 41 secured in the passage 39 has a port 42 therethrough normally closed by a valve 43 under urgency of a spring 44, which valve 43, however, is adapted to be opened by the suction or vacuum within the engine. Passage 40 is adapted to control a valve seat at 45 by a valve member 46 slid- 45 able through a disk 47 and having communication with the atmosphere and with the passage 40 through the medium of ports at 48. Port 42 50 also communicates with the atmosphere. A lever 49 is pivoted at 51 to a stud 52 on the block 21 55

and such lever at opposite ends through the medium of pins and elongated slots is operatively connected at 53 to the needle valve 46 and at 54 to a projection 55 on the poppet valve 43.

5 The heating chamber 27 is adapted to communicate with the exhaust line of the internal combustion engine and to receive the exhaust gases directly therein at the conduit or port 56. However, in lieu of the exhaust gases, heated air from any desired source and preferably from means on or adjacent to the exhaust manifold of the engine may be used instead of such exhaust. Said pipe 56 has two branches communicating with the chamber 27 as at 57 and 58, the former serving to better heat the mixing chamber. It will be apparent that the heating may be done by an electric heating coil within the heating chamber supplied from a battery or other source to serve the same purpose.

20 A stationary body 59 is disposed centrally of the inner cylinder 10 and a vertical shaft 60 is journaled therein having a fan at its top as at 61 for turbulence. Body 59 has a space 62 therein in which an impeller 63 is disposed and which is fastened to the shaft 60. A tube or conduit 64 is mounted in the cylinder walls 10 and 11 and communicates with the branch 58 and with the space 62, to conduct exhaust or other fluid to space 62 and operates impeller 63 through impact therewith, the medium escaping from the space 62 through a pipe 65 mounted in the wall of cylinder 10 and in the body and communicating with the heat chamber 27 and an outlet or discharge pipe 66 leads from the wall 11, in line with the said pipe 65. A suitable lubricator means may be provided at 67 to facilitate the lubrication of shaft 60 through the medium of a pipe 68 leading through the wall of cylinders 10 and 11 and through the body 59.

40 Disposed in the heating chamber 27 is a rod 69 adjustably fastened at 70 to the ring 12. Parallel with the rod 69 is a rod 71 which is slideable through the said ring 12 and the rods 69 and 71 are selectively connected together through pivotal connection with a lever 72, pivoted at 73 to the cylinder wall 11. Rod 71 extends through a lever 74 at an opening 75 and has adjustable engagement with such lever by means of a nut 76 threaded on the rod 71.

50 The lever 74 is pivoted at 77 to the plate 14. A contractile coil spring 78 is adjustably anchored at 79 to the casing 11 and is connected to a lateral arm 80 of the lever 74. A lever 81 extends from the valve 20 and is pivoted at 82 to a bracket or the like 83 secured to plate 14. Lug 84 on lever 81 engages the lever 74 and lever 81, at its outer end has a contractile coil spring 85 secured to it, and through the medium of a screw threaded eyelet member 86, is adjustably secured to the block 21. Lever 81 has an elongated slot at 87 in which a part 88 on the heater valve 26, is loosely connected.

65 The rods 69 and 71 are of a suitable metal which will expand when heated by the exhaust gases or other heating medium passing through the chamber 27, as for instance copper, brass or aluminum. Lever 74 is made of the same materials as said rods 69 and 71. It will be understood, that no limitation is to be implied since any equivalent thermostatic means may be substituted for one or all of the said parts 69, 71 and 74. Normally, the parts 69, 71 and 74 being cold or at normal temperature, the main fuel control valve 26 will be open to the maximum extent.

As the valve 26 is normally open to the maximum extent, when starting the motor rich fuel will be drawn from the pipe 23 past both of the valves 34 and 26, escaping from the former at passage 38 adjacent the throttle valve 17 and escaping from the latter through the orifices 28 into the mixing chamber or upper part of the cylinder 10, the necessary turbulence being created by operation of the fan 61 in coaction with the orifices 30. The port 19 will be open and under the control of the valve 20 according to temperature conditions, to admit air into the mixing chamber for admixture with the fuel escaping through jets 30. The exhaust gases pass through the branch 58, pipe 64 and operate the turbine 63 and then escape through pipe 65 into the heating chamber 27 and exhaust gases will also pass into said heating chamber 27 through the upper branch 57, serving to better heat such mixing chamber for more efficient vaporization.

20 The exhaust gases will efficiently preheat the fuel due to the fact that the pipes 26 and 31 are disposed in the chamber 27 and thus in the path of such exhaust gases to escape into the atmosphere through the outlet 66. As soon as the thermostatic means 69, 71 and 74 are heated by the exhaust gases, the engine will be capable of idling on the fuel passing through the passage 37, at which time, the thermostatic means expand and close the valve 26. The rich mixture will pass both valves 34 and 26 so as to be available for starting purposes only. The lever means 72 and 74 may be varied as desired to multiply the expansion of the thermostatic elements as far as desired.

30 It will be realized that the said high speed needle valve 26 through the connections described, will be controlled by the operation of the valve 20 controlling the admission of air into the mixing chamber, such valve 20 being normally urged to its seat by the spring 85.

35 The impeller 63 rather than being operated by exhaust gases or equivalent medium, may be operated in any suitable manner as by a charge from the cylinders of the motor direct, by an exploding jet or by compressed air furnished by various means.

40 Attention is called to the fact that the vacuum operated poppet valve 43 facilitates the bleeding of air into both the high speed and the idling jets. The decrease in vacuum in the intake manifold of the engine as the throttle 17 is opened allows spring 44 to close the valve 43 and apply all the vacuum to the fuel but as the vacuum again builds up under a stationary throttle, the valve is again drawn open and releases the vacuum on the jets by allowing air to enter with the fuel.

45 The various parts are preferably adjustable and particularly the poppet vacuum control valve 43 through the medium of tensioning of spring 44, adjustment of the fulcrum at 49, the high speed needle valve and of the expansion control system.

50 As best shown in Figure 4, I may employ an auxiliary air valve 90 coacting with a seat 91 in an elbow conduit 92 communicating with the atmosphere and with the mixing chamber or interior of the cylinder 10. Valve 90 is carried by a slideable stem 93 urged upwardly by a spring 94 abutting an adjustable nut 95 on the rod 93 and also abutting a spider 96 at the upper end of the conduit 92. Rod 93 by means of a link 97 is detachably and adjustably connected to a rod 98 extending from a piston 99 operating in

a cylinder 100 having an elbow pipe 101 in communication with the conduit section 15 and accordingly subject to the suction of the engine. A vent opening 102 is provided in the top wall of 5 the cylinder 100. Said air valve 91 is opened when the vacuum in the manifold is sufficient to overcome the spring tension on the spring means for closing the valve, this tension being adjustable as desired, the greater vacuum exerting a strong 10 pull on the piston 99 through pipe 101. When said throttle is open for accelerating or for more power, the vacuum in the manifold drops and said piston returns, thus closing the valve 90 and allowing a richer mixture. Adjustment of the 15 spring 94 at the nut 95, the point where the valve 90 operates, may be changed according to different conditions. At higher engine speeds, the vacuum in the manifold and in the carburetor combined hold the valve 90 open, relieving the 20 vacuum or suction on the main fuel supply.

Various changes may be resorted to provided they fall within the spirit and scope of the invention.

I claim as my invention:

- 25 1. A carburetor of the class described having a mixing chamber, a port for the intake of air to said mixing chamber, a valve member controlling said port, a conduit for the supply of fuel to the mixing chamber, a valve in said conduit, a lever connected to the valve and to the valve member, a thermostatic lever engaged by the last mentioned lever, a thermostatic rod operatively connected to the second mentioned lever, a thermostatic rod anchored to the carburetor, and multiplying lever means connecting said rods.
- 30 2. A carburetor of the class described having a mixing chamber, a port for the intake of air to said mixing chamber, a valve member controlling said port, a conduit for the supply of fuel to the mixing chamber, a valve in said conduit, a lever connected to the valve and to the valve member, a thermostatic lever engaged by the last mentioned lever, a thermostatic rod operatively connected to the second mentioned lever, a thermostatic rod anchored to the carburetor, and multiplying lever means connecting said rods, means pro-

viding a chamber into which said rods extend, and means for the admission of exhaust gases into said last mentioned chamber.

3. A carburetor of the class described having a mixing chamber, a port for the intake of air to said mixing chamber, a valve member controlling said port, a conduit for the supply of fuel to the mixing chamber, a valve in said conduit, a lever connected to the valve and to the valve member, a thermostatic lever engaged by the last mentioned lever, a thermostatic rod operatively connected to the second mentioned lever, a thermostatic rod anchored to the carburetor, multiplying lever means connecting said rods, means providing a chamber into which said rods extend, 10 means for the admission of exhaust gases into said last mentioned chamber, a conduit in the mixing chamber having outlet orifices for the fuel, a fan operable adjacent said orifices, a turbine to actuate said fan, and means to supply 15 exhaust gases to operate said turbine.

4. A carburetor of the class described having a conduit for the passage of fuel into the same, a branch passage leading from said first mentioned passage for idling adjustment, a valve controlling 25 the branch passage, thermostatic means operable to close the first mentioned valve and passage through heat of the engine, and means operable to bleed air into the first mentioned conduit and into the branch passage operable by vacuum in 30 the engine.

5. A carburetor of the class described having a conduit for the passage of fuel into the same, a branch passage leading from said conduit for idling purposes, a valve controlling the branch 35 passage, thermostatic means operable to close the valve and conduit through heat of the engine, and means operable to bleed air into the first mentioned conduit and into the branch passage operable by vacuum in the engine, including 40 valves coacting with ports associated with each passage, one of said valves being a vacuum operated valve, a lever connected to the last mentioned valve, and means pivotally mounting the lever.

JOSEPH HEWITSON. 45
